J. WHITE.
PRINTING PRESS.
APPLICATION FILED SEPT. 24, 1919.

Patented June 1, 1920.

INVENTOR
JOSEPH WHITE

by Clifford & Bull,
ATTYS

UNITED STATES PATENT OFFICE.

JOSEPH WHITE, OF MIDDLESEX, NEW JERSEY, ASSIGNOR TO HALL PRINTING PRESS COMPANY, OF DUNELLEN, NEW JERSEY, A CORPORATION OF NEW JERSEY.

PRINTING-PRESS.

1,341,693.

Specification of Letters Patent.

Patented June 1, 1920.

Application filed September 24, 1919. Serial No. 325,945.

To all whom it may concern:

Be it known that I, JOSEPH WHITE, a citizen of the United States, residing at Middlesex, county of Middlesex, State of New Jersey, have invented certain new and useful Improvements in Printing-Presses, of which the following is a specification.

This invention relates to printing presses in which provision is made for separating or tripping some or all of the cylinders at predetermined times, and particularly such a printing press in which the separation of the cylinders is controlled by the presence or absence of a sheet being fed to the press.

In some form of presses the printing surfaces are arranged so that they are normally in contact at the time when a sheet is brought to rest against the feed gages preparatory to being taken into the press. In such presses, if the separation of the cylinder is to be determined by the absence of a sheet at this gage, then the cylinders are separated when only partial impression has been made, thus spoiling one or more sheets.

This is particularly liable to occur in "offset" presses in which the tripping is brought about by moving one or more of the cylinders simultaneously.

One of the objects of my invention is to provide an arrangement by which the separation of the cylinders can be controlled from a point remote from the front gage so as to provide sufficient time to separate the cylinders before the printing surfaces thereon come into contact, and likewise to restore such cylinders to printing position so that the beginning of their surfaces will come into contact when a sheet has been presented at such remote point. Another object of my invention is to improve the tripping mechanism and provide such a device which will be readily controlled from a remote point.

With these and other objects in view, my invention consists of certain novel features of construction, combination and arrangement of parts as will be more fully described and pointed out in the appended claims.

In the drawings, Figure 1 is a sectional side elevation of one form of printing press to which my present invention has been ap-

plied, and Fig. 2 is an end elevation of one side of such a press.

The corresponding parts are referred to both in the specification and in the drawings 55 by similar reference characters.

In the illustrative form of press the side frames 10 support the bearings for the cylinders, 11 being the impression cylinder, 12 the offset or blanket cylinder and 13 the 60 form cylinder. The impression cylinder has an impression surface 14 and a set of sheet grippers 15 operated in the usual manner to close on the front edge of a sheet placed against the usual front gage 16, the 65 sheet in the form illustrated being carried down to the gage 16 by a series of endless tapes 17.

The offset cylinder 12 is provided with a printing surface 18 which is provided with the usual offset blanket, and the form cylinder 13 is provided with the impression surface 19 and the usual printing form which in this instance is a planographic plate. 20, 20 are the inking rollers.

In the illustrative form of press I have shown an arrangement for separating the form and blanket cylinders only, but it will be understood that a similar arrangement may be provided for separating the blanket 80 and impression cylinders. This latter separation is, however, of the usual type, and, as usually designed, is controlled by the absence of a sheet against the gage 16. Such an arrangement being well understood by 85 those skilled in the art, further illustration or description will be unnecessary to an understanding of my present invention.

The separation of the form and blanket cylinders in the illustrative form of my invention is brought about by mounting the bearings of the form cylinder 13 in an eccentric bushing 21 of the usual type, this bushing being connected by a rod 22 with an arm 23 connected to a shaft 24. It will be understood that the bushing 21 and arm 23 are duplicated on each side of the press. Attached to the shaft 24 is a double-ended arm 25 provided with pins 26 and 27. A fork 28 having projections 29 and 30, is mounted 100 to reciprocate between the pins 26 and 27 by means of a cam lever 31 pivoted at 32 and

carrying a cam roller 33, the fork 28 being pivoted at 34 to the cam lever 31. A cam 35 is attached to the cylinder 12 and cooperates with the roller 33, a spring 36 acting to hold the cam roller 33 on the cam 35. It will be evident that as the cam 35 rotates the fork 28 will be moved up and down. The distance between the pins 26 and 27 is such that when one side of the fork is against the pins 26, as shown in Fig. 1, the projection 30 is out of alinement with the pin 27, and similarly, when the projection 30 is in alinement with the pin 27, the projection 29 is out of alinement with the pin 26. In the arrangement illustrated the fork 28, which of course can turn around the pivot 34, is held normally in the position shown in Fig. 1 by a spring 37.

The lower end of the fork 28 has a cam-shaped projection or toe 39 which is engaged by a roller 40 on one end of a bell crank 41 provided with a spring rod 42 and spring 43 extending through a bearing 44. A toe 45 on the fork 28 engages with 25 the roller 40 to move the bell crank 41 to the position shown in the drawings, when the roller 33 drops to the lower part of the cam 35. The spring rod 42 is provided with a notch 46 which may be engaged by 30 a locking plunger 47 controlled by a solenoid 48 which is operated in the manner to be hereinafter described.

The parts are shown with the cylinders in contact, and until the solenoid 48 is operated the cylinders will remain in this condition, because as the fork 28 is raised by the cam 35 it will be held to the right of Fig. 1 by the spring 37, since the roller 40 is not locked and will therefore be moved 40 upward by the cam 39, thus drawing the rod 42 through the bearing 44.

Now, if the solenoid should be operated so that the plunger 47 will be moved up into the notch 46, the roller 40 will be held in the position shown in Fig. 1. As the fork 28 is raised by the cam 35 the roller 40 will provide a fixed abutment which will cause the fork 28 to swing to the left of Fig. 1 and bring the shoulder 30 into alinement with the pin 27, and the further movement of the fork 28 will turn the shaft 24 to partially rotate the bushings 21 to separate the cylinders.

If before the next reciprocation of the fork 28 the solenoid is made inoperative, so that the plunger 47 drops out of the notch 46, the fork 28 will drop to the position shown in Fig. 1, and at its next upward movement will be turned to the right 60 on its pivot 34 by the spring 37 and this will bring the shoulder 29 in engagement with the pin 26 and return the shaft 24 to its initial position, and thus bring the cylinders into printing relation again.

As will be understood by those skilled in the art, the length of the printing surfaces on the illustrative press, and the relative position, is such that if all three cylinders were separated simultaneously when a sheet is found to be absent from the gages 70 16 at the time when the grippers 15 are supposed to close thereon, the result would be an imperfect impression either from the form and the blanket or from the blanket and the sheet being printed. As usually 75 arranged, the cylinders are made to separate so as to avoid spoiling the impression surface, and this results in an imperfect impression on the blanket from the form cylinder. I obviate this difficulty by providing a detector at a point remote from the gages 16 and connect this detector with the trip as through the solenoid 48, so that if a sheet has not arrived at the detector 80 the form and blanket cylinders will be separated before the printing surfaces thereon come into contact. Such a detector I have illustrated more or less diagrammatically as comprising a pendulum member 50 contacting with a roller 51, the tapes 17 carrying 90 a sheet between 50 and 51. The member 50 is carried on one end of a bell crank 52 controlled by a cam 53 through a cam lever 54 and a connecting rod 55. A battery or other source of power 56 is connected to 95 the solenoid 48 and also has one terminal connected to the roller 51 and the other to the pendulum member 50. As shown in Fig. 1, the detector is set sufficiently remote from the gage 16 so as to give sufficient 100 time for the cylinders to be separated before the printing surfaces come to the contacting point in the event that no sheet is presented between 50 and 51. The cam 53 raises and lowers the member 50 so as to 105 break the connection with the solenoid 48 each time after it has been established, and then such connection is attempted to be restored by the lowering of the member 50, such connection being prevented if a sheet 110 has in the meantime been presented to the roller 51. When the solenoid 48 is energized the plunger 47 is moved upward into the notch 46 as heretofore described.

It will be seen that the detector of my present invention is entirely independent of any detector which may be used in connection with the gage 16 to separate the form and the blanket cylinders, or indeed entirely independent from any form of tripping mechanism between these two last mentioned cylinders, and such cylinders may be tripped at any time desired to prevent their contact without reference in any way to the separation of the blanket and form cylinders.

It will be obvious that many features of my present invention may be applied to any

form of press, and that the several features of the invention may be used independently of each other.

I claim:

- 5 1. In a printing press, having a form cylinder, a blanket cylinder and an impression cylinder, a feed gage to position a sheet being fed to the impression cylinder, means to forward a sheet to said gage, the printing 10 surfaces on the form and blanket cylinders being constructed and arranged so that they are normally in contact at the time a sheet is taken from said gage by said impression cylinder, tripping means to separate the 15 blanket and the form cylinders, and means, controlled by the presence or absence of a sheet in said sheet-forwarding means at a point remote from said gage, to actuate said tripping means to separate said 20 cylinders before the printing surfaces thereon come into contact.

2. In a printing press, a pair of printing cylinders, means to separate said cylinders, a feed gage independent of said cylinders 25 and arranged to position a sheet in relation to said printing cylinders, means to forward a sheet to said gage and means controlling the operation of said cylinder-separating means and adapted to be rendered operative 30 by the absence of a sheet in said sheet-forwarding means at a point remote from said gage.

3. In a printing press, a pair of printing cylinders, a feed gage to position a sheet in relation to said printing cylinders, means to forward a sheet to said gage, the printing surfaces on said cylinders being constructed and arranged so that they are normally in contact at the time a sheet is taken from said 40 gage, tripping means to move said cylinders into and out of contact, and a detector mechanism arranged to be acted on by a sheet in the control of said forwarding means before the sheet reaches the gage, said detector mechanism and said tripping mechanism being constructed and arranged to move the cylinders apart before their surfaces contact when no sheet is presented to said detector mechanism.

4. In a printing press, a pair of printing cylinders, a feed gage to position a sheet in relation to said printing cylinders, means to forward a sheet to said gage, the printing surfaces on said cylinders being constructed 55 and arranged so that they are normally in contact at the time a sheet is taken from said gage, tripping means to move said cylinders into and out of contact, and a detector mechanism arranged to be acted on by a sheet in the control of said forwarding 60 means before the sheet reaches the gage, said detector mechanism and said tripping mechanism being constructed and arranged to move the cylinders apart before their sur-

faces contact when no sheet is presented to 65 said detector mechanism, and to bring the cylinders together before their surfaces contact when a sheet is presented to said detector mechanism.

5. In a printing press, a pair of printing 70 cylinders and means for moving said cylinders toward and away from each other, comprising a reciprocating member adapted to be held in either one of two positions, to trip or to untrip said cylinders, yielding 75 means to hold said member normally in untripping position, a normally yielding abutment adapted to cause said member to move into tripping position when said abutment is fixed, and means to hold said abutment in 80 its fixed position.

6. In a printing press, a pair of printing cylinders and means for moving said cylinders toward and away from each other, comprising a reciprocating member adapted to 85 be held in either one of two positions, to trip or to untrip said cylinders, yielding means to hold said member normally in untripping position, a normally yielding abutment adapted to cause said member to move 90 into tripping position when said abutment is fixed, a detector adapted to be actuated by a sheet being fed to the cylinders and means actuated by said detector when no sheet is presented thereto to hold said abutment in 95 its fixed position.

7. In a printing press, a pair of printing cylinders and means for moving said cylinders toward and away from each other, comprising a reciprocating member adapted to 100 be held in either one of two positions, to trip or to untrip said cylinders, yielding means to hold said member normally in untripping position, said member having a cam thereon, a normally yielding abutment 105 co-operating with said cam and adapted to cause said member to move into tripping position when said abutment is fixed, and means to hold said abutment in its fixed position.

8. In a printing press, a pair of printing cylinders and means for moving said cylinders toward and away from each other, comprising a reciprocating member adapted to be held in either one of two positions, to trip 115 or to untrip said cylinders, yielding means to hold said member normally in untripping position, said member having a cam thereon, a normally yielding abutment co-operating with said cam and adapted to cause said member to move into tripping position when said abutment is fixed, a detector adapted to be actuated by a sheet being fed to the cylinders and means actuated 120 by said detector when no sheet is presented thereto to hold said abutment in its fixed position.

9. In a printing press, a pair of printing

1
cylinders and means for moving said cylinders to and away from each other, comprising a reciprocating member adapted to be held in either one of two positions, to trip or to untrip said cylinders, yielding means to hold said member normally in untripping position, a normally yielding abutment adapted to cause said member to move into

tripping position when said abutment is fixed, a detent to hold said abutment in its fixed position, a solenoid to control the position of said detent, a pair of terminals connected with said solenoid and adapted to be held apart by a sheet being fed to said cylinders.

JOSEPH WHITE.
